CLAIM

The ornamental design for a wall holder for an earplug dispenser, as shown and described.

DESCRIPTION

FIG. 1 is a front left side perspective view of a wall holder

for an earplug dispenser according to our new design;

FIG. 2 is a front elevational view thereof;

FIG. 3 is a side elevational view thereof and with the other side being a mirror image;

FIG. 4 is a top plan view thereof; and,

FIG. 5 is a bottom plan view thereof.
